DISPLAY RACK

Leo H. Bernstein, 9370 W. Bay Harbor Drive,
Miami Beach, Fla.

Filed Sept. 21, 1961, Ser. No. 66,792

Term of patent 7 years

(Cl. D80—9)

FIG. 1

FIG. 2

FIG. 3

I claim:

The ornamental design for a display rack, substantially as shown.
